UNITED STATES PATENT OFFICE.

FRANK DUTCHER, OF VERSAILLES, AND PHILIP PETER, OF PITTSBURG,
PENNSYLVANIA.

RAILWAY SIGNAL-TORPEDO.

No. 823,998.

Specification of Letters Patent.

Patented June 19, 1906.

Application filed December 28, 1904. Serial No. 233,651.

To all whom it may concern:

Be it known that we, FRANK DUTCHER, residing at Versailles, and PHILIP PETER, residing at Pittsburg, in the county of Allegheny and State of Pennsylvania, citizens of the United States, have invented certain new and useful Improvements in Railway Signal-Torpedoes, of which the following is a specification, reference being had therein to the accompanying drawings.

Our invention relates to improvements in railway signal-torpedoes adapted for use in connection with railway train service; and the primary object in view is to provide a simple and efficient construction and combination of parts whereby the use of metallic or other hard material for the torpedo-shells is avoided in order that the danger and injury to persons caused by flying pieces of the metallic torpedoes now commonly used by railroads is entirely done away with and which makes the use of our torpedo perfectly safe and harmless.

A further object of this invention is to provide a simple and efficient means for attaching the rail-engaging straps to a non-metallic torpedo case or box.

Our present invention has in view other objects and advantages consequent to the construction of our improved non-metallic torpedo, which will appear from the following description of the novel features of our construction.

This improved railway signal-torpedo is illustrated in the drawings, in which—

Figure 1 is a perspective view of a two-part-case torpedo embodying our invention and showing in connection therewith an improved manner of attaching the rail-engaging straps thereto. Fig. 2 is a cross-sectional view thereof, taken longitudinal the rail-engaging strap. Fig. 3 is a sectional view similar to Fig. 2, showing our invention applied to a three-part torpedo-case. Fig. 4 is a perspective view of a torpedo embodying our invention, showing another way of connecting thereto the rail-engaging strap. Fig. 5 is a perspective view showing our improved torpedo with a spring or steel rail-engaging strap attached thereto. Fig. 6 is an interior perspective view of one of the cup-shaped parts of our improved torpedo.

In order to enable our invention to be fully understood, we will now describe it by reference to the accompanying drawings, in which 55 1 is the case or box in which the detonating material is contained. This case may consist of an outer or top part 1^a and an inner or bottom part 1^b, which are placed together, as illustrated in Fig. 2, and the two parts consist of fibrous material—such as paper or cloth, preferably the former—for the purpose of cheapness. As shown, the outer part 1^a of the case is cup-shaped in cross-section, and preferably the inner or bottom part 1^b is 60 similarly shaped, and one is telescoped within the other in inverse positions with the detonating or explosive mixture 2 between them.

The primary feature of our present invention is the application of a strengthening, resisting, and holding ring or band 3, which is placed around the edge of the case, as shown. Preferably this band or ring is made of paper or cloth, so that the complete torpedo is 75 composed of non-metallic and harmless material, though the band may be made of metal in some instances for the purpose and reasons hereinafter mentioned.

A paper or soft fibrous torpedo made as 80 above described is found in actual practice to be absolutely harmless, as the parts thereof fly very few feet, and to make a loud report.

In order to make a torpedo which will be practical under the varied conditions which 85 they are used, it must be waterproof. To this end the holding or strengthening band or ring performs an essential feature of our paper or soft-fiber torpedo in that it holds the flange of the outer part 1^a of the case 90 against spreading out and in close contact with the inner or bottom part 1^b of the case. Furthermore, as it is necessary to coat the torpedo with a suitable waterproofing compound the edges thereof form in practice an 95 increased width of circumferential surface at the vital point 4 of the torpedo for the reception of the compound. As the junction of the flanges of the cup-shaped bottom or inner part 1^b of the torpedo-case is necessarily 100 rounding, as shown, a circumferential groove or recess 5 is formed which will retain the waterproofing compound at the vital point, and the surrounding ring or band holds the

parts from spreading or loosening up and causes the waterproof compound to effectually prevent the entrance of moisture between the two parts of the case.

5 As shown, we prefer to make the ring or band of a thicker material than the parts of the case, which adds strength and stability to the completed device. The ring or band also adds the lateral resisting power of the torpedo at the point needed when exploded, and therefore increases its detonating report. In operation the top and bottom of the torpedo are caught between the wheel and the rail, making lateral resistance the more essential 10 to obtain a loud explosion.

Before the parts of the torpedo are assembled they are preferably subjected to a suitable waterproofing compound to prevent moisture soaking therethrough into the explosive compound. To further prevent moisture getting to the explosive compound by passing between the two parts of the case, we coat the inner side of the flange of the outer part 1^a, as shown at 7, Fig. 6. In filling 15 the case the explosive compound is placed in the inner cup-shaped part 1^a, another outer or cover cup-shaped part 1^a placed thereover. In the placing of the two parts together the edge of the flange of the inner part will scrape 20 part of the waterproofing compound and carry it down and make a waterproof circumferential joint at the point 8, Fig. 2, and when a three-part case is used, as shown in Fig. 3, the inner side of the flange of the outer 25 part is likewise coated with waterproof compound, and a second waterproof circumferential joint is formed at 9, Fig. 3.

Our improved manner of attaching the rail-engaging strap to our new torpedo is shown 30 in Figs. 1 and 2. This consists in causing the holding, resisting, and strengthening band or ring to perform the further function of uniting a rail-engaging strap 10 to the torpedo-case. It is accomplished by placing the rail-engaging 35 strap across the top of the case and down opposite edges thereof and then passing the band over the strap and around the edge of the case. In this way the band or ring is caused to hold the parts of the torpedo, 40 strengthen it, form a lateral explosive resistance, and attach the rail-engaging strap to the torpedo-case.

When the torpedo is completed, it is dipped 45 into a suitable waterproofing compound, which will flow into the crevices or grooves, and the parts held from separating by the band, and the waterproofing compound prevents from loosening up.

When a spring or steel rail-engaging strap 50 11 is to be used, as shown in Fig. 5, the band or ring will be made of strong material, such as cloth, or in some instances metal.

Any suitable manner of attaching the rail-engaging strap to our improved torpedo-case 55 may be used without affecting that part of

our present invention. One suitable manner is shown in Fig. 4, though we claim our improved manner in which the band performs that function in substantially the manner shown in Figs. 1 and 2.

We desire it understood that modifications and variations of our invention may be made without departing from the spirit and scope of our invention as averred by the appended claims.

While we have described and particularly desired to produce a fibrous torpedo for the reasons fully explained, yet we wish it understood that the feature of the ring or band may be advantageously used in connection 75 with a metal torpedo for uniting thereto a rail-engaging member, and in such case the ring or band may be made of metal.

Our fibrous band or ring is advantageous in preventing the cutting and acute bending 80 of the lead strap, which, as is well known in metallic torpedoes, causes the quick breaking of the lead strap, and consequently numerous useless torpedoes in the hands of the consumer. The fibrous band provides a cushion 85 for the lead strap where it is folded around the torpedo-case, as it always is in shipping and when being handled by the user. In this way our improved fibrous band increases the life of the lead strap and 90 prevents acute bends thereof and will practically eliminate useless torpedoes or culs in the hands of consumers.

Having thus described our invention, what we claim, and desire to secure by Letters Patent, is—

1. An improved device of the character described comprising a several-part case made of fiber, and a strengthening and holding ring for the edge thereof to strengthen and hold 95 the parts of the case together.

2. An improved device of the character described, comprising a fibrous case composed of telescoping members, and a holding, strengthening and resisting ring for the edge 105 of the case.

3. An improved device of the character described, comprising a fibrous case and a fibrous ring surrounding the edge of the case for the purpose described.

4. An improved device of the character described, comprising fibrous case and a band surrounding the edge of the case for the purpose described the band being of a width substantially equal to the thickness of the case.

5. An improved device of the character described, comprising a fibrous case and a fibrous band of a width substantially equal to the thickness of the case and surrounding the edge thereof for the purpose described.

6. An improved device of the character described, comprising a case composed of flanged telescoped members, and a fibrous band of a width substantially equal to the thickness of the telescoped members surrounding the edge 130

of the outer member for the purpose described.

7. An improved device of the character described, comprising a case having an edge, a rail-engaging strap passed across the case and across its edge, and a ring surrounding the edge of the case, and embracing the rail-engaging member.

8. An improved device of the character described, comprising a case having an edge, a ring passing around the edge of the case, and a rail-engaging member connected with the ring.

9. An improved device of the character described, comprising a case having an edge, a rail-engaging member, and a ring passing around the edge of the case and clamping the rail-engaging member between the ring and the case.

10. A device of the character described, comprising a several-part fibrous case having an edge, a rail-engaging member and a fibrous ring surrounding the edge of the case uniting the rail-engaging member to the case and

strengthening and holding the parts of the 25 fibrous case to proper position.

11. A waterproof fibrous device of the character described, comprising two telescoped cup-shaped members, the inner side of the flange of the outer member provided with a coat of waterproof compound, whereby by the telescoping of the parts form a circumferential waterproof ridge at the inner edge of the flange of the inner member.

12. An improved device of the character described, comprising an explosive case, a lead-rail-attaching device connected with the case, and a fibrous band surrounding the edge of the case which will provide a cushion for, and prevent acute bends of the lead strap 40 when it is wrapped around the case.

In testimony whereof we affix our signatures in presence of two witnesses.

FRANK DUTCHER.
PHILIP PETER.
